UNITED STATES PATENT OFFICE.

CLARENCE D. PLATT, OF BRIDGEPORT, CONNECTICUT, ASSIGNOR TO HENRY D. SEARS,
OF BOSTON, MASSACHUSETTS.

SNAP SOCKET-SHELL.

1,086,080.

Specification of Letters Patent.

Patented Feb. 3, 1914.

Application filed July 8, 1908, Serial No. 442,599. Renewed July 2, 1913. Serial No. 777,099.

To all whom it may concern:

Be it known that I, CLARENCE D. PLATT, a citizen of the United States, residing at Bridgeport, county of Fairfield, State of Connecticut, have invented a new and useful Snap Socket-Shell, of which the following is a specification.

This invention has for its object to provide simple and inexpensive means for locking the members of electric socket shells together, important features of the invention being that the cost of production is reduced to the minimum, the use of threads, bayonet joints and screws being avoided and the parts formed complete by few and simple mechanical operations; that the parts are locked against longitudinal detachment when merely pushed together, and that when the locking lug and locking recess are in engagement the members are locked against any movement whatever.

With these and other objects in view I have devised the simple and novel mode of attaching the members of an electric socket shell together which I will now describe, referring to the accompanying drawing forming a part of this specification and using reference characters to indicate the several parts:

Figure 1 is an elevation of my novel socket shell with the members locked together; Fig. 2 a plan view of the body on an enlarged scale; Fig. 3 a detail sectional view on the line 3-3 in Fig. 2, looking in the direction of the arrow; and Fig. 4 is a similar view, the upper end of the body being pressed inward to disengage the locking lug from the locking slot.

10 and 11 denote the members, 10 indicating the body and 11 the cap of an electric socket shell. The body is provided at its upper end with the usual slot, indicated by 12, to receive the key of the switch (not shown), with attaching lugs 13 and with a locking lug 14 placed near the key slot. The attaching lugs are formed by pressing out the metal of the body and are rounded on the top and sides as at 15. The lower sides of said lugs, however, comprise abrupt locking shoulders indicated by 16. The locking lug is likewise formed by pressing out the metal of the body and is preferably placed vertically above one of the attaching lugs so that said lugs may be formed at the same operation. The locking lug is rounded as

at 17 so as not to interfere with the attachment and detachment of the parts and is provided on its sides with abrupt locking shoulders 18. The cap is provided near its lower end with an annular internal locking shoulder 19 and with a locking recess 20, the side walls of which are adapted to be engaged by the locking shoulders 18 of the locking lug when in the engaging position.

The operation is as follows: The lower end of the cap receives the upper end of the body. The members are attached by simply moving them together longitudinally in any circumferential position and the locking against withdrawal is effected the instant the internal shoulder on the cap passes over the attaching lugs on the body, and the parts are locked against any movement by rotating one part relatively to the other until the locking lug snaps into the locking recess. I have shown a socket shell provided with three attaching lugs. It will be obvious, however, that the number of these lugs is wholly unimportant so far as the principle of the invention is concerned. As the upper ends of both the locking and attaching lugs are rounded, it is perfectly easy to slide the two parts together, the spring of the metal permitting the annular shoulder on the cap to pass freely over the lugs. As soon as the annular shoulder has passed the attaching lugs, however, the locking shoulders 16 on said lugs will engage the annular shoulder and lock the parts securely against withdrawal but not against rotation. Partial rotation of the cap and body relatively to each other will place the locking lug on the body in alinement with the locking recess in the cap, the locking lug snapping to place and the locking shoulders 18 thereon engaging the side walls of the recess and effectually locking the parts against any movement. To detach the cap the operator simply presses inward slightly upon the body sufficiently to disengage the locking lug from the locking recess. The cap may then be readily removed, the side of the cap having the locking recess being raised first.

Having thus described my invention, I claim:

1. A socket shell comprising members provided with means for attaching the same together, said means consisting of attaching lugs and a locking lug upon one part and an internal annular shoulder and a locking re-

cess upon the other part, said members engaging when moved together longitudinally and locking when rotated after engagement.

2. A socket shell comprising a body and a cap, said parts being provided respectively with attaching lugs and locking lugs and with an internal annular shoulder and a locking recess, so that said parts will be attached when moved together longitudinally 10 in any position and locked against any movement when rotated to place the locking lug in engagement with the locking recess.

3. An electric lamp socket having a shell and cap fitting together telescopically and 15 provided with automatic latching means brought into engagement by simple endwise movement of the parts with relation to each

other, in any relative rotary position of the said parts, said cap and shell being provided with means to prevent the shell from turning when so latched, said parts being readily detachable from each other. 20

4. An electric lamp socket having shell and cap, together with readily freed engaging means therefor latching in any relative 25 rotary position of the parts and means for preventing rotary movement of the parts with relation to each other.

In testimony whereof I affix my signature, in presence of two witnesses.

CLARENCE D. PLATT.
